UNITED STATES PATENT OFFICE.

FREDERICK R. DICKEY, OF BUTLER, PENNSYLVANIA.

COMBINED LETTER OPENER, PAPER KNIFE, AND SEAM RIPPER.

Application filed February 10, 1923. Serial No. 618,315.

To all whom it may concern:

Be it known that I, FREDERICK R. DICKEY, a citizen of the United States, residing at Butler, in the county of Butler and State of Pennsylvania, have invented certain new and useful Improvements in Combined Letter Openers, Paper Knives, and Seam Rippers; and I do hereby declare the following to be a full, clear, and exact description of the invention, such as will enable others skilled in the art to which it appertains to make and use the same.

The invention provides an article adapted for a variety of uses and comprising a blade and handle, the latter being of such construction as to enable the utilization of discarded blades of safety razors, the device being particularly adapted for use as a letter opener, a paper knife or for ripping 20 seams.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to 30 without departing from the nature of the invention.

Referring to the accompanying drawings forming a part of the application:

Figure 1 is a perspective view of an implement embodying the invention,

Figure 2 is a perspective view of the stem removed from the handle and extended, the full lines showing the normal position of the blade and the dotted lines different positions 40 of the blade when placing the same in position or removing it from the stem,

Figure 3 is an enlarged side view of a portion of the stem with the blade in position, and

Figure 4 is a perspective view of end portions of the members comprising the stem showing more clearly the matching recesses and projections.

Corresponding and like parts are referred to in the following description and designated in the several views of the drawings by like reference characters.

The device comprises a handle 1, a stem 2 and a blade 3. The handle 1 may be of 55 any construction and design and has an opening in which the stem 2 is detachably

fitted, this being essential to admit of the ready replacement of the blade 3.

The stem 2 may be of any formation and cross sectional outline and comprises complementary members 4 and 5 which are pivotally connected at one end, as indicated at 6, the opposite end of the stem being insertable in the handle 1, whereby to hold the members in proper position when the blade 3 is confined between them. One of the members is provided in its length with projections 7 and 8 and the companion member has corresponding recesses 9 and 10, the projection 7 being disposed at the pivot 60 end of the members and the projection 8 a short distance therefrom. When the members 4 and 5 are turned so as to lie one against the other, the projections 7 and 8 enter the matching recesses 9 and 10 and engage openings of the blade 3 and retain it 65 in place between the members.

The blade 3 preferably consists of a safety razor blade in which a series of openings 9 are formed to receive projections of the holder in a manner well understood. Usually three openings are formed in the blade 3 and the end openings are equally spaced from the middle opening. In the present instance, the projections 7 and 8 are spaced 75 apart a distance to receive the end openings of the blade 3.

In applying the blade, the members 4 and 5 are removed from the handle 1 and either is moved into the dotted line position shown 80 in Figure 2. The free end of the member 5 is passed through one of the end openings in the blade 3 and the blade is moved along the member 5 until the blade is in position to be swung into a position where the projection 7 is received in the end opening of 85 the blade through which the member 5 has passed. The member 5 is then swung on the pivot 6, and the parts brought into the full line position shown in Figures 1, 2 and 3, where the blade lies upon the member 4 with the projections 7 and 8 entering the outer and inner openings, as shown most clearly by the full lines in Figure 2. When the blade becomes dull or otherwise unfitted 95 for further effective service, it may be discarded and replaced by another safety razor blade which is unfitted for shaving but well adapted for use as a letter opener, paper knife or seam ripper.

It will be noted that the stud 6, which pivotally connects the members 4 and 5 of

the stem, projects from the projection 7 which passes through one of the end openings in the blade 3. This structure permits an end portion of the blade 3 to extend 5 beyond the stem 2, to present a scraping edge. The arrangement mentioned, wherein the end of the blade extends beyond the forward end of the stem, is of material advantage owing to the fact that the blade is 10 flexible and may be pressed almost flat against any hard surface, as in the removing of paint from glass, or in removing a stamp from an envelope. It is further to be noted, that the members 4 and 5 forming the 15 stem 2, are relatively narrow and flat, and that there are no exposed edges or points to interfere with the use of the implement when the same is being used as seam ripper, paper knife or the like.

20 What is claimed is:

1. A device of the character specified comprising a blade having spaced openings, a stem including a pair of complemental members between which said blade is adapted to be positioned, one of said members having spaced projections on its inner side to enter said openings, means carried by one of said projections and pivoting said members together, said blade adapted to be placed in position between said members by threading one of said members through an opening in the blade and having the opening through which the member is threaded receive the projection which carries the pivoting 35 means.

2. A device of the character specified comprising a blade having spaced openings, a stem including a pair of complemental members between which said blade is adapted to be positioned, one of said members having spaced projections on its inner side to enter said openings, one of said projections arranged at the forward end of said members, means carried by the last mentioned projection and permanently pivoting the forward ends of said members together to adapt said members for relative swinging movement in their respective parallel planes, and said blade adapted to be positioned between 40 said members by threading one of said members through an opening in the blade and

having the opening through which the member is threaded receive the end projection which carries the pivoting means.

3. A device of the class described comprising a stem including a pair of complemental members, one of said members having spaced projections on its inner side, a blade having openings to receive said projections, means pivoting the other of said members to one of said projections, and a removable handle receiving the rearward end of said stem and holding the parts of the device in position.

4. A device of the character specified comprising a stem including complemental relatively narrow bars, means pivoting said bars together at their forward ends, one of said bars provided upon its inner side with projections and the other of said bars provided on its inner side with matching recesses, a blade having openings in its length to receive said projections and one of said openings having the pivot means passing therethrough, said blade adapted to be 55 clamped between said relatively narrow bars, the bars engaging a portion of the blade intermediate its longitudinal edges and extending beyond the rearward edge of the blade, and a handle detachably engaging the 60 rearward ends of the bars, said handle engaging said bars to hold the parts of the device in position when assembled.

5. A device of the character specified comprising a handle, a stem including companion members having their rearward ends detachably connected to the handle, means pivotally connecting the forward ends of said members, a blade positioned between the members with the forward end of the 75 blade projecting beyond the forward ends of the members, and means securing the blade between the members against movement relative thereto, the pivoting means for the members engaging one of the securing 80 means.

In testimony whereof I affix my signature in presence of two witnesses.

FREDERICK R. DICKEY.
